UNITED STATES PATENT OFFICE.

ETHAN I. DODDS, OF PITTSBURGH, PENNSYLVANIA, ASSIGNOR TO FLANNERY BOLT COMPANY, OF PITTSBURGH, PENNSYLVANIA.

STAY-BOLT STRUCTURE FOR BOILERS.

Application filed October 3, 1921. Serial No. 504,888.

To all whom it may concern:

Be it known that I, ETHAN I. DODDS, a citizen of the United States, and a resident of Pittsburgh, in the county of Allegheny and State of Pennsylvania, have invented certain new and useful Improvements in Stay-Bolt Structures for Boilers; and I do hereby declare the following to be a full, clear, and exact description of the invention, such as will enable others skilled in the art to which it appertains to make and use the same.

This invention relates to improvements in staybolt structures for boilers,—one object of the invention being to provide simple and efficient means to facilitate the application of the parts to a boiler sheet in such manner that the closure devices of the structure shall be effectually clinched to the boiler sheet.

With this and other objects in view, the invention consists in certain novel features of construction and combinations of parts as hereinafter more fully described and pointed out in the claims.

In the accompanying drawings, Figures 1 and 2 are sectional views showing an embodiment of my invention, and Figures 3 to 20 are views of modifications.

The outer sheet of a boiler is represented at 1 and provided with a bolt hole 2, the wall of which latter is made rounded to form a seat for the rounded or partly-spherical head 3 of a staybolt 4, whereby the latter may have a flexible connection with the boiler sheet. In the embodiment of the invention shown in Figures 1 and 2, the rounded head 3 of a staybolt is made with diametrically opposite recesses 5 and the walls 6 at the inner ends of said recesses are made inclined in opposite directions respectively.

A ring or sleeve 7 having external screw threads 8 is located over the bolt opening 2 in the boiler sheet and provided at diametrically opposite points with fingers 9. These fingers are bendable so that when their inner ends are made to engage the inclined walls 6 of the recesses 5 and the ring 7 is forced inwardly or downwardly, said fingers will be bent so that their inner or lower ends will be caused to project laterally from the inner end of the bolt opening in the boiler sheet and become disposed under or behind

the inner face of the latter as indicated in Figure 2. An internally threaded closure 10 engages the external threads 8 of the ring 7 and between this closure and the outer face of the boiler sheet, a washer 11 is disposed. If desired the outer face of the boiler sheet may be made with an annular recess or depression to receive said washer.

It is apparent that when the parts shall have been assembled in the manner above described, and the closure 10 is screwed down against the washer on the boiler sheet, the ring 7 will be caused to move slightly in an outward direction and the hooked inner ends of the fingers 9 caused to tightly or firmly engage the inner side of the boiler sheet, and thus the closure devices will be securely clinched to the boiler sheet. It will be understood that the recesses 5 in the bolt head are of such size relatively to the proportions of the fingers 9 that free movement of the bolt head on its seat in the boiler sheet will not be interfered with and therefore the flexible connection of the bolt with the boiler sheet will be maintained.

In the embodiment of the invention shown in Figure 3, a clincher sleeve 12 is provided and made with depending or inwardly projecting fingers 13 having shoulders 14 at their inner ends to engage the inner face of the boiler sheet 1^a. In this construction the recesses 5^a in the bolt head 3^a may have their inner end walls but slightly inclined. The sleeve 12 is threaded externally to receive the internal threads of the cap or closure 10 and the edge portion of this cap or closure rests against a washer 11 seated on the boiler sheet.

In Figure 4 of the drawing, I have shown a ring 12^a having an inwardly projecting annular flange 12^b forming shoulders 12^c and 12^d. In this construction the shoulder 12^c rests on a washer 12^e on the outer face of the boiler sheet and the fingers 13 pass through the bolt opening and through recesses in the wall of the latter (as in Figure 3) and are provided at their inner ends with shoulders 14 to engage the inner face of the boiler sheet. The ring 12^a is threaded internally to receive an externally threaded cap or closure 10^a and between the inner edge of this cap and the shoulder 12^a in the ring

12^a, a washer 12^c may be disposed. If desired the ring 12^a may be welded to the boiler sheet as indicated at 15.

If desired the upper or outer end portion 5 of the fingers 13 may be bent as indicated at 16 Figure 5 and made to project from the inner or lower edge of the ring 12^a instead of projecting straight down or inwardly from the latter, as in Figure 3. Likewise 10 the upper ends of the fingers 13 may be bent laterally as at 17 so that said fingers will be disposed in vertical planes (as seen in Figure 6) inwardly removed from the inner edge of the flange 12^b of the ring 12^a.

15 In the construction shown in Figures 7 and 8, the bolt head 3^b is formed with diametrically opposite recesses, such as indicated at 18 and a one-piece cap or closure 19 is employed. Fingers 20 project from the 20 inner face of this cap or closure near the edge portion of the latter,—said fingers first projecting inwardly and then downwardly through the bolt opening in the boiler sheet and provided at their inner ends with shoulders 25 21 to engage the inner face of said boiler sheet. In this construction a portion of the wall of the bolt opening is made cylindrical as at 22 and a portion is made rounded as at 23 to form the seat for the 30 bolt head and the fingers 20 lie against the cylindrical wall of said bolt opening.

In the construction shown in Figures 9 to 13 inclusive, the bolt head 24 and a portion of the bolt 25 is provided with recesses 26 35 having the shape indicated in Figures 10, 12 and 13. A cap or closure 27 is provided with an internally threaded portion 28 to receive an externally threaded ring or head 29. This ring is formed with integral laterally projecting arms 30 and from the latter, integral fingers 31 project in a direction to pass through the bolt opening in the boiler sheet and through the recesses in the bolt head. If desired a washer may be located between 40 the cap or closure 27 and the outer face of the boiler sheet, or, if desired, this cap or closure may be welded to the boiler sheet. Instead of making the head of the staybolt as shown in Figure 13 it may have the shape 45 shown at 24^a Figure 14, or instead of providing the head of the staybolt with two oppositely disposed recesses, said head may have the form shown at 24^b Figure 15.

In the construction shown in Figures 16 55 and 17, the bolt and its head has substantially the same form as that shown in Figures 9, 10, 12 and 13, but in Figures 16 and 17 I have shown an externally threaded ring 32 having an angular opening 33 and fingers 34 to extend through the bolt opening in the boiler sheet and provided with shoulders to engage the inner face of said boiler sheet. The ring or sleeve 32 is screw threaded externally for the accommodation of threads 60 65 within a cap or closure 35 and between the

latter and the outer face of the boiler sheet a washer 36 may be disposed.

In the construction shown in Figures 18, 19 and 20, a cap or closure 37 to be mounted on the boiler sheet 1^b, is threaded internally 70 to receive a ring 38 and this ring is made with a slightly tapering inner wall 39 for the accommodation of a bearing member 40 for the head 41 of a staybolt 42. The threaded ring 38 is provided with a plurality of 75 fingers 43 provided near their free ends with recesses 44 to receive a head 45 at the lower or inner end of the bearing member 40.

Having fully described my invention what I claim as new and desire to secure by Letters-Patent, is:

1. In a staybolt structure, the combination with a boiler sheet having a bolt opening, of a clincher member having a part passing through the boiler sheet adjacent to said bolt opening and engaging the inner portion of the boiler sheet, said clincher member provided with means forming a closure over the bolt head.

2. In a staybolt structure, the combination with a boiler sheet having a bolt opening, and a headed staybolt, of a clincher member having a part projecting through the boiler sheet adjacent to the bolt opening and engaging the inner portion of the boiler sheet, 95 and a closure member having threaded connection with said clincher member and co-operable therewith and with the boiler sheet to firmly secure said clincher member to the boiler sheet and effect a rigid connection of 100 the closure with the boiler sheet.

3. In a staybolt structure, the combination with a boiler sheet having a bolt opening, of a staybolt provided with a head having a recess, a closure, and a member connected with said closure and passing through the boiler sheet and the recess in the bolt head, said member having a part to engage the inner portion of the boiler sheet.

4. In a staybolt structure, the combination with a boiler sheet having a bolt opening, of a staybolt provided with a head having recesses, a closure member to seat on the boiler sheet, and clincher fingers co-operable with said closure member and projecting through the boiler sheet and through the recesses of the bolt, said clincher fingers provided at their free ends with parts to engage the inner portion of the boiler sheet in proximity to the bolt opening in the latter.

5. In a staybolt structure, the combination with a boiler sheet having a bolt opening with a rounded wall, of a staybolt having a rounded head to seat on the rounded wall of the opening in the boiler sheet, said head having recesses forming inclined inner walls, an externally threaded ring provided with fingers to project through the bolt opening in the boiler sheet and through the recesses in the bolt head whereby the inclined inner 125 130

walls of said recesses will cause said fingers to bend and engage the inner portion of the boiler sheet in proximity to the bolt opening in the latter, and an internally threaded cap or closure engaging said externally threaded ring, the edge portion of said cap or closure being cooperable with the outer portion of the boiler sheet.

In testimony whereof, I have signed this specification in the presence of two subscribing witnesses.

ETHAN I. DODDS.
